BEVERAGE CARTON HOLDER

William G. Hunt, Laurinburg, N.C.

Application November 18, 1958, Serial No. 53,414

Term of patent 14 years

(Cl. D58—26)

The side not shown is the same as the side shown.

I claim:

The ornamental design for a beverage carton holder, as shown and described.
